UNITED STATES PATENT OFFICE

ALBERT S. SAMUELS, OF SAN FRANCISCO, CALIFORNIA

DESIGN FOR A RING

Application filed May 20, 1932. Serial No. 43,857. Term of patent 14 years.

To all whom it may concern:

Be it known that I, ALBERT S. SAMUELS, a citizen of the United States, residing at the city and county of San Francisco, State of California, have invented a new, original, and ornamental Design for a Ring, of which the following is a specification, reference being had to the accompanying drawing, forming part thereof.

The figure is a perspective view of a ring embodying my design. The side of the ring not shown is identical to the side shown in the drawing.

I claim:

The ornamental design for a ring substantially as shown and described.

ALBERT S. SAMUELS.
